US0D1085189S

(12) **United States Design Patent** (10) **Patent No.:** **US D1,085,189 S**
(45) **Date of Patent:** **** Jul. 22, 2025**

(54) **APPLIANCE**

(71) Applicant: **Sunbeam Products, Inc.**, Boca Raton, FL (US)

(72) Inventor: **Anna Caldwell**, Boca Raton, FL (US)

(73) Assignee: **Sunbeam Products, Inc.**, Atlanta, GA (US)

(**) Term: **15 Years**

(21) Appl. No.: **29/865,348**

(22) Filed: **Jul. 20, 2022**

(51) **LOC (15) Cl.** **15-10**

(52) **U.S. Cl.** **D15/146**
USPC **D15/146**

CLAIM

The ornamental design for an appliance as shown and described.

DESCRIPTION

FIG. 1 is a perspective view of a first embodiment of an appliance;

FIG. 2 is a top plan view of the appliance of FIG. 1;

FIG. 3 is a front elevation view of the appliance of FIGS. 1 and 2;

FIG. 4 is a right side elevation view of the appliance of FIGS. 1-3;

FIG. 5 is a rear elevation view of the appliance of FIGS. 1-4;

FIG. 6 is a bottom plan view of the appliance of FIGS. 1-5;

FIG. 7 is a perspective view of a second embodiment of an appliance;

FIG. 8 is a top plan view of the appliance of FIG. 7, the front elevation, right side, rear elevation, and bottom plan views of FIGS. 3, 4, 5, and 6 being identical views of the appliance of FIG. 7, respectively;

FIG. 9 is a perspective view of a third embodiment of an appliance; and,

FIG. 10 is a top plan view of the appliance of FIG. 9, the front elevation, right side, rear elevation, and bottom plan views of FIGS. 3, 4, 5, and 6 being identical views of the appliance of FIG. 7, respectively.

The broken lines in the drawings depict portions of the appliance that form no part of the claimed design.
